UNITED STATES PATENT OFFICE.

JOHN HUNT, OF DUMONT, COLORADO.

CLIMBING-ELEVATOR DEVICE.

1,348,138.

Specification of Letters Patent.

Patented July 27, 1920.

Application filed June 12, 1919. Serial No. 303,595.

To all whom it may concern:

Be it known that I, JOHN HUNT, a citizen of the United States, residing at Dumont, in the county of Clear Creek and

5 State of Colorado, have invented certain new and useful Improvements in Climbing-Elevator Devices; and I do declare the following to be a full, clear, and exact description of the invention, such as will enable others skilled in the art to which it appertains to make and use the same.

10 My invention relates to improvements in elevators and more particularly to a machine of this class adapted to climb a track 15 at the side of a building.

One object of the invention is to provide an elevator which may be propelled both vertically and horizontally along the side of a building, thus well adapting it for use 20 as a fire-escape and for fire fighting.

Another object is to provide an elevator which may be drawn along the ground, for instance by fire apparatus, and which may be quickly engaged with a vertical track on 25 a building, to scale the side thereof. Thus, by equipping all buildings with the vertical tracks and providing the fire companies with the improved elevators, the occupants of any building may be quickly and easily 30 carried to safety in case of fire, and the fire may be advantageously fought by using the elevator to carry fire hose or other equipment, in addition to carrying the firemen to the most advantageous points.

35 Another object is to provide an elevator of the class described which may well be used in the construction of buildings, for elevating building material and carrying it to the particular part of the building at 40 which it is to be used.

Other objects are to provide an elevated horizontal track and a carriage thereon for supporting the vertical track; to make novel provision for propelling the machine along 45 said vertical track; to provide a novel arrangement of drums and cables operated from the elevator for propelling the carriage along the track; to devise novel brake means for controlling the descent of the elevator; to provide efficient means for locking the elevator car against descent when it is moving horizontally; and to provide wheels for guiding the car either when traveling along the ground or along the side 50 of a building.

With the foregoing in view, the inven-

tion resides in the novel constructions and arrangements of parts hereinafter described and claimed, and shown in the accompanying drawings.

60

Figure 1 is a front elevation of my invention.

65

Fig. 2 is a side elevation showing the elevator climbing vertically along the side of a building.

Fig. 3 is a side elevation with one side of the elevator car removed to illustrate the interior parts thereof.

Fig. 4 is a front elevation with the casting of the car in section as indicated by line 70 4-4 of Fig. 3.

Fig. 5 is a horizontal section on approximately the plane of line 5-5 of Fig. 3, illustrating the main driven shaft and the means coöperating therewith for propelling 75 the machine vertically and horizontally.

Fig. 6 is a horizontal section cut centrally through the parts shown in elevation in Fig. 5 and further illustrating one of the brakes in section.

80

Fig. 7 is a vertical section on the plane of line 7-7 of Fig. 5, showing more particularly the gear shifting means and one of the brakes.

Fig. 8 is a vertical section on the plane of 85 line 8-8 of Fig. 6, showing the wheel for propelling the elevator car vertically and the means for holding said wheel in engagement with the vertical track.

Fig. 9 is a side elevation partly in section of the chain of which the vertical track is preferably constructed.

90

Fig. 10 is primarily a vertical section on the line 10-10 of Fig. 9, parts however being shown in edge view.

95

Figs. 11 and 12 are vertical sections on the planes indicated by the lines 11-11 and 12-12 respectively of Fig. 5.

Fig. 13 is a detail section as indicated by line 13-13 of Fig. 11.

100

Fig. 14 is a horizontal section on substantially the plane of line 14-14 of Figs. 3 and 15 showing more particularly the pedal mechanism and the brake therefor.

Fig. 15 is a vertical section on the plane of line 15-15 of Fig. 14.

Fig. 16 is a vertical section as indicated by line 16-16 of Fig. 14.

Fig. 17 is a vertical section on the plane of line 17-17 of Figs. 14 and 16.

110

Fig. 18 is a detail vertical section showing a different position of the steering le-

ver from that shown at the right hand side of Fig. 16.

Fig. 19 is an enlarged elevation partly in section, showing the means on the end of the 5 steering lever for connecting it with the steering chain.

Fig. 20 is a detail elevation partly in section illustrating one manner of mounting the steering lever.

10 Fig. 21 is a small side elevation illustrating the manner in which the elevator car may be operated from a hoisting engine on the ground, instead of by self-contained driving means.

15 Fig. 22 is an enlarged vertical section on the plane of line 22—22 of Fig. 21.

Fig. 23 is a side elevation showing the manner in which the car may travel along the ground.

20 In carrying out my invention, I provide a vertical track 1, and mount an elevator car 2 on said track for moving along the same, said track being by preference supported by a carriage 3 which is mounted on a horizontal elevated track 4. This track may be supported in any preferred manner but I have shown brackets 5 carrying the same and extending from the side of a building 6. Carried by the car 2 are a foot pedal mechanism or other suitable driving means, and gearing and the like for propelling said car along the track 1 and for propelling the carriage 3 along the horizontal track 4; and I also equip said car with suitable brake and 35 locking means for controlling or preventing its descent, and with wheels which may be turned to different positions for guiding the travel of the car. This car may either be permanently mounted on the track 1 or 40 may be detachable therefrom and portable from one building to another, to be drawn for instance by fire apparatus, and the aforesaid wheels are instrumental in steering the machine when it is drawn along the ground. 45 The several features of the machine and one manner of constructing each of them, are illustrated fully in the accompanying drawings and are specifically described below, but it is to be understood that the present disclosure is for illustrative purposes only, and that all construction shown and described 50 may be in numerous other forms.

The carriage 3 may be of any suitable construction, but I prefer to provide a hook-like hanger bar 7 having a peripherally grooved propelling wheel 8 traveling on the track 4, the depending end of said hanger bar having arms 9 for contact with the outer side of the track to prevent the wheel 8 55 from possibly canting and jumping the track. Connected with the wheel 8 for rotation therewith, and preferably mounted on the same shaft with said wheel, are two drums 10, and oppositely wound on said 60 drums are a pair of cables 11 which depend

to the car 2 and are here wound on drums 12 which may be independently rotated or operated in unison. When the car is moving vertically along the track 1, the cables 11 are wound onto or unwound from the drums 12, and the drums 10 are not then rotated. These drums 10 however are operated by winding either of the cables 11 on its drum 12 and simultaneously paying out the other cable, and by this means, the carriage 3 may be 75 propelled horizontally along the track 4 to move the entire elevator horizontally. The means for driving the drums 12 and otherwise controlling the movement thereof, will be hereinafter described in detail, but before a clear understanding of such driving means may be had, it will be necessary to consider the mechanism for propelling the car vertically along the track 1, since the drum driving means is dependent upon said 80 propelling means.

Mounted horizontally in the car 2, is a suitable frame 13 including a plurality of parallel bars 14 having suitable bearings for all of the shafts mounted on the frame. 90 A main driven shaft 15 is mounted on the frame 13 and is provided with spur gears 16 for mesh with larger gears 17 which are secured on a second shaft 18. Shaft 18 is provided with a propelling wheel 19 secured thereon and engaging the track 1, and in most instances I prefer to embody the wheel 19 in the form of a sprocket, and to form the track 1 of a sprocket chain, a suitable guide wheel 20 being provided to hold the 100 chain and sprocket in mesh with each other. By driving the shaft 18 from the shaft 15, by the gearing 16—17 or other preferred means, the wheel 19 is caused to travel along the track 1, thus propelling the entire machine upwardly along said track. Gravity may be relied upon to lower the device, and to control the speed of the lowering operation, I provide the shaft 18 with a suitable 105 brake.

The brake above mentioned, by preference consists of three disks 21 fixed on the shaft 18, and brake levers 22 disposed between the central disk and the others, the shape and mounting of these levers being most clearly 115 illustrated in Figs. 6 and 7. At each side of the central disk I preferably provide two of the levers 22, said levers being curved over and under the shaft 18 and secured together at one end as seen at 23, while their other ends may well be guided by contact with a horizontal shaft 24 which may carry the wheel 20 as shown in Fig. 6. I intend to cant the levers 22 into contact with the disks 21 and thus frictionally control the 125 rotation of the shaft 18, and although this could be done in a number of ways, I by preference employ a rock shaft 25 having a head or the like 26 between the two sets of levers, whereby turning of said shaft will 130

operate said head to cant the levers in the required manner. A suitable casing 27 may be provided to contain the brake mechanism, and to mount the shaft 25, and obviously any suitable means could be employed for turning said shaft. I have shown however a crank arm 28 on the upper end of shaft 25, connected by a link 29 with the upper end of a hand lever 30 which is shown, 10 for instance in Figs. 7, 8, 11 and 12.

The wheels 19 and 20 may be suitably incased, for instance in an enlargement 31 between the ends of a tubular guide 32 for the chain or track 1, said guide being by 15 preference provided with flared ends 33. The enlargement 31 and the parts therein are most clearly illustrated in Figs. 5, 6 and 8.

Mounted on the frame 13 in parallel relation with the shafts 15 and 18, are two short shafts 34 which are disposed in alignment with each other, said shafts fixedly carrying gears 35 for mesh with the gears 16 when the latter are moved out of mesh 25 with the gears 17. This may be done by shifting the entire shaft 15 laterally within slots 36 in the bars 14, and although any suitable means may be used for so shifting the shaft 15, I prefer to mount a pair of 30 links 37 on said shaft and to slidably support said links at one end on the shafts 34, as indicated at 38. Above links 37, I provide a rock shaft 39 (see Figs. 5, 7, 8 and 11), said shaft having depending arms 40 35 suitably connected with the links 37 for shifting the latter when said shaft is turned, and for turning the shaft in question, I may provide a hand lever 41. To lock this lever in position to hold the gears 16 in mesh 40 either with the gears 17 or 35, suitable means such as a slot 42 in the lever, and a clamping bolt 43 passing through said slot, may well be provided.

Slidable on the shafts 34, are two sprocket 45 wheels 44, said wheels being movable to one position at which they are locked to the shaft, and being shiftable to another position at which they are free of connection with said shaft, and suitable means such as 50 the levers 45 may be used for shifting the sprocket wheels to either position. Any adequate means may be employed to lock the levers 45, but I prefer to provide shouldered links 46 passing through slots 47 in said 55 levers as illustrated most clearly in Figs. 11 and 13. Sprocket chains 48 are trained around the sprockets 44 and around other sprockets secured to the drums 12, and it will thus be seen that by operating the 60 proper lever 45, one chain or the other may be driven to in turn drive the required drum 12, thus moving the carriage 3 along the track 4. When this operation takes place, the car is usually locked against descent by 65 any preferred means.

For the purpose of winding the cables 11 during the ascent of the car and for unwinding them as said car descends, and for allowing the drums 12 to be driven by the chains 48 when the car is held against vertical movement, I provide novel means for driving the drums in question from the shaft 18, this means being shown in the form of pulleys 50 and 51 mounted respectively on the shaft 18 and the drums 12, and belts 52 75 trained around said pulleys, these belts being preferably equipped with suitable tighteners 53. By this arrangement, as long as the shaft 18 rotates and drives the propelling wheel 19 to move the carriage along 80 the track 1, the pulleys 50, belts 52 and pulleys 51, drive the drums 12 to either wind or pay out the cables 11, according to the direction in which the car is moving. When the car is to be held against vertical movement and propelled horizontally, one or the other of the chains 48 is thrown into play by its respective lever 45, thus positively driving one drum or the other to operate the means 11-10 to shift the carriage 3. During 90 the rotation of the drum which is being positively driven by its chain 48, the pulley 51 of said drum will slide upon the belt 52, and at the same time a corresponding sliding will take place with respect to the other 95 drum, which must rotate to allow its respective cable to unwind, and this last named action will insure that the cable will be taut at all times in readiness for action when its use is necessary.

Any suitable means could be provided for driving the shaft 15, but I prefer to equip said shaft with a large sprocket 54, to train a sprocket chain 55 around said sprocket, and to drive said chain from a small 105 sprocket 56 on a main driving shaft 57, said shaft being provided with cranks 58 having foot pedals 59 as illustrated for instance in Figs. 3, 14, 15 and 16. It is intended that a suitable number of persons shall operate the pedals 59 to drive shaft 15 and that from this shaft, either of the means for moving the car vertically and horizontally, shall be driven. I wish it understood that in some instances, I may 110 provide means other than the foot pedals for operating the machine, but I prefer them since this form of power is more reliable than others.

To hold the entire car against possible 120 dropping at any point to which it is raised, I provide a dog 60 coacting with the chain 55, and this dog is by preference arched, as seen in Figs. 14, 15, 16 and 17, with its legs straddling the sprocket 56 and pivotally mounted on the shaft 57. I prefer to locate dog 60 between the legs of an arched standard 61 rising from the bottom of the elevator car and carrying means for releasing said dog when required. I have shown 125 130

this means in the form of a rock shaft 62 mounted on the standard 61, a crank arm 63 extending from said rock shaft and suitably connected with the dog, and a hand lever 64 for operating said rock shaft. Suitable means 65 may be used if desired to hold the lever 64 in one position or the other. In most instances, I will equip the shaft 57 with a brake mechanism 66 of any adequate form, and since the construction of the mechanism shown is practically identical with the brake means of the shaft 18, it will not be further described. In addition to the several brakes, I prefer to provide a pin 67 carried by the car 2 for projection through the chain 1 to positively hold the car against descent, whenever required. This pin is illustrated most clearly in Figs. 14, 15, 16 and 17, and although any suitable means could be employed for projecting and retracting said pin, I preferably securely mount the same on the end of a sliding bar 68 operating in guides 69 under the floor of the car. A horizontal lever 70 and a vertical lever 71 may be employed for operating the bar 68.

The wheels 72 of the car are carried by shafts 73 suitably mounted in brackets or the like 74 and provided with sprockets 75. A steering chain 76 is trained around the several sprockets 75 and by means of a hand lever or the like 77, said chain may be shifted to simultaneously position the wheels either vertically or horizontally, for traveling in either direction along the side of a building, and manipulation of said lever will also steer the machine when it is being drawn or propelled along the ground. Lever 77 and its mounting and locking means are illustrated most fully in Figs. 16, 17, 18, 19 and 20. The lever in question passes through an opening 78 in the side of the elevator car and is mounted on a bar 79 which spans said opening as indicated in Fig. 20. The bar 79 may be provided with a notch 80 and with a finger 81 projecting into said notch and the lever 77 may well be fulcrumed on this finger and held against removal therefrom by a slide 82 which may be held by a set screw or the like 83. The free end of the lever 77 is preferably provided with a projecting finger 84 for projection through the chain 76, and a hooklike bifurcated slide 85 is provided with an eye 86 receiving the outer end of said finger, said slide being adjustably clamped to the lever by suitable means 87. In assembling, the finger 84, the slide 85 allows any necessary adjustment according to the distance which the chain 76 may be spaced from the side of the car 2.

For illustrative purposes, I have shown a slide 88 mounted on the bar 79 and having a vertical part 89 for holding lever

77 in either one position or the other as illustrated in Figs. 16 and 18.

The car 2 may of course be of any adequate construction and may be provided at one side with a doorway 90 partly closed by a downwardly swinging door 91. This door may be swung downward to open position and will at the same time bridge the gap between the building and the car, to allow persons to enter and leave the device. A sliding door 92 may be provided at the opposite side of the car to permit the occupants to leave when they have been carried to the ground. A suitable seat 93 may be provided if desired.

The chain 1 is preferably constructed as seen in Figs. 9 and 10, of parallel opposed links 1^a having slots 1^b in their ends, the inner ends of said slots being enlarged, and other links 1^c having headed studs 1^d received in said slots. The heads of the studs 1^d prevent separation of the links until moved to the enlarged inner ends of the slots and this arrangement therefore prevents separation of the chain links in case any of the tie bolts 1^e which connect the opposed links, should break. These tie bolts may well carry rollers 1^f and certain of them may pass through the studs 1^d.

Assuming that the car 2 is permanently mounted on the track 1, the operation of the machine is as follows: To travel upwardly, the shaft 15 is driven by the pedal mechanism or other means provided therefor, and the lever 41 is operated to shift the shaft 15 so as to mesh the gears 16 and 17. This drives shaft 18 and causes the sprocket 19 to climb along the chain or track 1. During this operation, the pulleys 50 drive the belts 52 to rotate the drums 12 in a direction to wind the cables 11, thus preventing entanglement thereof, and any necessary variations in speed between the drums and the shaft 18 are allowed by slippage of the belts. When the car has been elevated to the required extent, it will be held against dropping by the dog 60 but as an additional precaution, the pin 67 may be projected through the chain 1. If the car is now to be shifted laterally, the lever 41 is actuated to mesh the gears 16 and 35, thus throwing the vertical propelling means out of play and disposing the horizontal propelling means for use. The lever 77 is now operated to turn the wheels 72 to horizontal positions and one or the other of the sprockets 44 is shifted into locking engagement with its respective shaft 34, while the other sprocket 44 remains loose upon the shaft. When the shaft 15 is now driven, the gears 16 and 35 drives the shaft 34 and the sprocket 44 locked thereto, thus operating one of the chains 48 to drive one of the drums 12. The cable 11 of this drum is thus wound, with the result that the drums 10 are turned in

one direction, thus rotating the propelling wheel 8 and causing the carriage 3 to move in one direction along the track 4. The other cable 11 is in the meantime being wound 5 upon its respective drum 10 and unwound from the drum 12 on which it is attached, the necessary turning of this drum being allowed by slippage of its respective belt 52. When the carriage 3 is to be shifted in the 10 opposite direction, the other chain 48 is thrown into play while the one previously in use remains idle by properly shifting its sprocket 44.

In order to descend, the dog 60 and the 15 pin 67 are released and the machine then lowers by gravity, its speed being controlled by the brake mechanism of either or both of the shafts 18 and 57.

By elevating the device and moving it 20 horizontally to the required extent, it may be shifted to any window of a building and thus the occupants may be quickly and easily carried to safety in case of fire, and the fire may be fought by carrying firemen, hoses 25 and equipment to the most advantageous points.

When the device constitutes a part of a portable fire apparatus, the car 2 is towed or otherwise carried to the fire and may be 30 quickly engaged with the track 1 and the cables 11, which remain permanently on the carriage 3 with which all buildings may be equipped.

In addition to the uses above enumerated, 35 the elevator is of advantage in the erection of buildings and may then be operated as seen in Figs. 21 and 22. In these figures, all construction is the same as above described, with the exception that the shaft 40 57' which drives the sprocket chain 55, is provided with a drum 100 on which a cable 101 is wound, said cable passing around a suitable sheave 102 adjacent the ground and being wound on a windlass 103. This wind- 45 lass may well be driven by an ordinary hoisting engine or by a motor vehicle. If desired, a platform 104 may be suspended from the car 2 for elevating building material and carrying it to any required part 50 of the building.

It will be understood that the different gears employed may be fastened to their shafts in any desired manner but I prefer to make such gears with squared openings 55 in their centers to fit squared portions of the shafts so that there will be no possibility of the gears becoming loose from the shafts during the operation of the device, as would be the case if the gears were fastened by 60 removable keys. This construction it will be readily seen will tend to lessen the liability of accident in the operation of the device.

From the foregoing, taken in connection 65 with the accompanying drawings, the con-

struction, operation and advantages of my improved elevator device will be readily understood without requiring more extended explanation, but I wish to emphasize the fact that the present disclosure is for illustrative purposes only and that in the manufacture of the machine, numerous changes may be made as occasion may dictate, within the latitude allowed by the appended claims. 75

I claim:

1. In a machine of the class described, an elevated horizontal track and a carriage thereon, a vertical track depending from said carriage, a car movable along said vertical track, means carried by said car for propelling it along said vertical track, and means operable from said car for propelling said carriage along said horizontal track. 80

2. In a machine of the class described, an elevated horizontal track, a carriage having a propelling wheel movable along said track, drum and cable means for rotating said propelling wheel, a vertical track depending from said carriage, a car movable along 90 said vertical track, means carried by said car for moving it along said vertical track, and means carried by said car for operating said drum and cable means to propel said carriage along said horizontal track. 95

3. In a machine of the class described, an elevated horizontal track, a carriage having a propelling wheel movable along said track, drum and cable means for rotating said propelling wheel, a vertical track depending from said carriage, a car movable along said vertical track, means carried by said car for moving it along said vertical track, and means carried by said car for operating said drum and cable means to propel said carriage along said horizontal track and for winding said cable means as said car travels upwardly. 100

4. In a machine of the class described, an elevated horizontal track, a carriage having a propelling wheel movable along said track, drum means carried by said carriage and connected with said propelling wheel for rotating the same, cables wound oppositely on said drum means and depending therefrom, a vertical track depending from said carriage, a car and means for moving it along said track, and drums carried by said car for winding said cables to operate said propelling wheel. 110

5. In a machine of the class described, an elevated horizontal track, a carriage having a propelling wheel movable along said track, drum means carried by said carriage and connected with said propelling wheel 125 for rotating the same, cables wound oppositely on said drum means and depending therefrom, a vertical track depending from said carriage, a car and means for moving it along said track, a pair of drums carried 130

by said car for winding said cables, and a positive and a non-positive drive for said drums, the non-positive drive being operated by said car moving means.

- 5 6. In a machine of the class described, an elevated horizontal track and a carriage on said track, a vertical track depending from said carriage, a car movable along said vertical track, driving means carried by said car, 10 means for propelling said car vertically, means for propelling said carriage horizontally, and means for engaging either of said propelling means operatively with said driving means.
- 15 7. In a machine of the class described, an elevated horizontal track, a carriage on said track, a vertical track depending from said carriage, a car movable along said vertical track, means for propelling said car along 20 said vertical track, means for propelling said carriage along said horizontal track, including a pair of cables and a pair of drums on said car on which said cables are wound, means for driving said drums from said car propelling means and for 25 permitting continued rotation of said drums after arresting the movement of said propelling means, and additional means for then positively driving either of said drums.
- 30 8. In a machine of the class described, an elevated horizontal track, a carriage having a propelling wheel on said track, a vertical track depending from said carriage, a car movable along said vertical track and 35 having a propelling wheel traveling thereon, driving means carried by said car and including a driven shaft, a second shaft carrying said propelling wheel of said car, means for driving said second shaft at will 40 from said driven shaft, means for rotating the propelling wheel of said carriage including a pair of cables and a pair of drums on said car on which said cables are wound, means for driving said drums from said 45 second shaft and for allowing continued turning of said drums after arresting the movement of said second shaft, and means for then driving either of said drums at will from said driven shaft.
- 50 9. In a machine of the class described, an elevated horizontal track, a carriage having a propelling wheel on said track, a vertical track depending from said carriage, a car movable along said vertical track and 55 having a propelling wheel traveling thereon, driving means carried by said car and including a driven shaft, a second shaft carrying said propelling wheel of said car, means for driving said second shaft at will 60 from said driven shaft, means for rotating the propelling wheel of said carriage, including a pair of cables and a pair of drums on said car on which said cables are wound, belts and pulleys for driving said drums 65 from said second shaft and for permitting

continued rotation of said drums after arresting movement of said second shaft, and means for then driving either of said drums at will from said driven shaft.

10. In a machine of the class described, 70 an elevated horizontal track and a carriage thereon, a vertical track depending from said carriage, a casing having guiding means through which said vertical track passes, a horizontal frame in said casing, 75 a driven shaft mounted on said frame, a second shaft on said frame parallel with said driven shaft and having a propelling wheel engaging said vertical track, gearing on said shafts and means for shifting 80 said driven shaft laterally to throw such gearing into and out of mesh; means for propelling said carriage along said horizontal track, including a pair of depending cables and a pair of drums mounted in 85 said casing above said frame, pulleys on said second shaft and on said drums and belts passing around said pulleys for driving said drums and permitting further rotation thereof when rotation of said second shaft is discontinued, additional gearing mounted on said frame for mesh with the gearing of said driven shaft when the latter gearing is shifted out of mesh with the gearing of said second shaft, sprockets, and 90 means for operatively connecting them from said additional gearing, other sprockets on said drums, and sprocket chains trained around the two sets of sprockets.

11. In a machine of the class described, 100 a vertical track, a car movable along said track, means in said car for propelling it along the track, including a foot operated shaft, and a sprocket chain driven thereby, and a dog coacting with said chain to hold 105 it against retrograde movement.

12. In a machine of the class described, a vertical track, a car movable along said track, means in said car for propelling it along the track, including a foot operated 110 shaft, a sprocket on said shaft, and a sprocket chain trained around said sprocket, an arched standard through the legs of which said shaft passes, an arched dog pivoted on said shaft between said arch legs and 115 coacting with said chain to hold the latter against retrograde movement, and means mounted on said standard for releasing said dog.

13. In a machine of the class described, 120 a horizontal track for disposition adjacent the top of the wall of a building, a carriage movable along said track, and means for propelling said carriage; a vertical track depending from said carriage, a car movable along said vertical track and means for so moving said car; a plurality of guide wheels for said car adapted to travel along said wall, and means for turning said wheels horizontally or vertically, according 125 130

to the direction in which the car is to be moved.

14. In a machine of the class described, a horizontal track for disposition adjacent the top of the wall of a building, a carriage movable along said track and means for propelling said carriage; a vertical track depending from said carriage, a car movable along said vertical track and means for so moving said car; a plurality of guide wheels for said car adapted to travel along said wall, a handle movable to two positions, and connecting means between said handle and said wheels for turning the latter simultaneously to either horizontal or vertical position by one movement of said handle.

15. In a machine of the class described, a horizontal track for disposition adjacent the top of the wall of a building, a carriage movable along said track and means for propelling said carriage; a vertical track depending from said carriage, a car movable along said vertical track and means for so moving said car; a plurality of guide wheels for said car adapted to travel along said wall, horizontal shafts mounted rotatably on said car and carrying said wheels, sprockets on said shafts, a sprocket chain trained around said sprockets, and means for moving said sprocket chain to position said wheels horizontally or vertically.

16. In a machine of the class described, a horizontal track for disposition adjacent the top of the wall of a building, a carriage movable along said track and means for propelling said carriage; a vertical track depending from said carriage, a car movable along said vertical track and means for so moving said car; a plurality of guide wheels for said car adapted to travel along said wall, horizontal shafts mounted rotatably on said car and carrying said wheels, sprockets on said shafts, a sprocket chain trained around said sprockets, and a lever extending through an opening in the side of said car and connected with said chain for operating it to position said wheels either vertically or horizontally.

17. In a machine of the class described, a horizontal track for disposition adjacent the top of the wall of a building, a carriage movable along said track and means for propelling said carriage; a vertical track de-

pending from said carriage, a car movable along said vertical track and means for so moving said car; a plurality of guide wheels for said car adapted to travel along said wall, horizontal shafts mounted rotatably on said car and carrying said wheels, sprockets on said shafts, a sprocket chain trained around said sprockets, a lever connected with said sprocket chain for operating it to turn said wheels either horizontally or vertically, the side of said car having an opening through which said lever extends, a bar spanning said opening and supporting said lever, and a slide movable along said bar for holding said lever in either position.

18. In a machine of the class described, a horizontal track for disposition adjacent the top of the wall of a building, a carriage movable along said track and means for propelling said carriage; a vertical track depending from said carriage, a car movable along said vertical track and means for so moving said car; a plurality of guide wheels for said car adapted to travel along said wall, horizontal shafts mounted rotatably on said car and carrying said wheels, sprockets on said shafts, a sprocket chain trained around said sprockets, a lever fulcrumed on the car and having a finger extending through said sprocket chain, a hook-like slide mounted on said lever and having an eye receiving said finger and means for securing said slide to said lever.

19. In a machine of the class described, a vertical chain, a car having a vertical tubular guide with flared ends and an enlarged intermediate portion, said guide receiving said chain, a propelling sprocket in said enlargement meshing with said chain, means for driving said sprocket, and another wheel in said enlargement for holding said chain in mesh with said sprocket.

20. A machine of the class described comprising a car having wheels adapted to travel on the ground when moving from place to place, or to travel along the wall of a building, and climbing means carried by said car and adapted to travel along a track at the side of the building.

In testimony whereof I have hereunto set my hand.

JOHN HUNT.
